CLAIM

The ornamental design for a soldering iron, as shown and described.

DESCRIPTION

FIG. 1 is a top perspective view of a soldering iron;

FIG. 2 is a side elevation view of the soldering iron of FIG. 1, the side elevational view taken from the side opposite that of FIG. 2 being identical.

FIG. 3 is a rear elevational view of the soldering iron of FIG. 1;

FIG. 4 is a front elevational view of the soldering iron of FIG. 1;

FIG. 5 is a top view of the soldering iron of FIG. 1;

FIG. 6 is a bottom view of the soldering iron of FIG. 1;

FIG. 7 is a top perspective view of a soldering iron;

FIG. 8 is a side elevation view of the soldering iron of FIG. 7, the side elevational view taken from the side opposite that of FIG. 8 being identical.

FIG. 9 is a rear elevational view of the soldering iron of FIG. 7;

FIG. 10 is a front elevational view of the soldering iron of FIG. 7;

FIG. 11 is a top view of the soldering iron of FIG. 7;

FIG. 12 is a bottom view of the soldering iron of FIG. 7;

FIG. 13 is a top perspective view of a soldering iron;

FIG. 14 is a side elevation view of the soldering iron of FIG. 13, the side elevational view taken from the side opposite that of FIG. 14 being identical.

FIG. 15 is a rear elevational view of the soldering iron of FIG. 13;

FIG. 16 is a front elevational view of the soldering iron of FIG. 13;

FIG. 17 is a top view of the soldering iron of FIG. 13; and,

FIG. 18 is a bottom view of the soldering iron of FIG. 13.

The broken line portions of the drawings are included for the purpose of illustrating unclaimed structure and form no part of the claimed design.
